UNITED STATES PATENT OFFICE.

CHARLES ASHTON HENRY BULLOCK, OF LONDON, ENGLAND.

AUTOMATIC FEEDING DEVICE FOR PRINTING PRESSES.

Application filed July 23, 1923. Serial No. 653,313.

To all whom it may concern:

Be it known that I, CHARLES ASHTON HENRY BULLOCK, a subject of the King of Great Britain, and a resident of London, England, have invented a certain new and useful Improvement in Automatic Feeding Devices for Printing Presses, of which the following is a specification.

This invention has reference to the automatic feeding of paper to a printing press sheet by sheet.

The object of the present invention is to provide a new and improved method of separating the sheets one by one preparatory to feeding whereby sheets of paper of any thickness may be removed and in a more effectual manner than heretofore and with this object in view the present invention consists broadly of an automatic feeding device for printing presses wherein the outer sheet of a series of stacked sheets of paper is separated, preparatory to removal, by being forced back against an abutment so as to cause the sheet or a portion or corner thereof to buckle and permit the remaining sheets to be held leaving the outer sheet free to be removed.

In order that the invention may be clearly understood an embodiment of the same will now be described with reference to the accompanying drawings in which:

Fig. 1 is a side elevation of a rotary hand press embodying a feeding device according to this invention showing the paper retaining device in the lowered position.

Fig. 2 is a rear view of the same looking towards the back of the paper magazine or delivery board.

Fig. 3 is a fragmentary plan view of the feeding device showing the operation of buckling the corner of the top sheet of paper on the magazine or delivery board.

Fig. 4 is a fragmentary side elevation of the feeding device showing the paper retaining device in the raised position.

Fig. 5 is a fragmentary view to an enlarged scale of a detail hereafter to be described.

In the application of the invention shown in the drawings the rotary press shown comprises an endless chain 1 on each side of the machine carrying between them the inking and impression rollers 2 and 3 which chains pass over sprocket wheels 4 at each end of the press one of which wheels is rotated by means of a handle 5 so as to cause the roll-

ers 2 and 3 to pass continuously over and under the chase or form 6. The automatic feeding device comprises an inclined magazine or delivery board 7 which is pivoted at 8 to a frame 9 which frame in turn is bolted or otherwise secured at an angle to one end of the frame 10 of the press.

The lower end of the magazine or delivery board 7 is resiliently supported through the medium of a roller 11 carried at the end of an arm 12 which arm in turn is mounted upon a pivot spindle 13 extending across the rear of the delivery board 7. This spindle 13 is biased by means of springs 14 so as to cause the roller 11 always to press firmly against the back of the board 7 and operate to normally hold the lower end of the board in the raised position.

The paper which is stacked on the board 7 is automatically fed sheet by sheet by means consisting of a clamping device or pressure stop 15, a buckling device 16 and a feeding finger 17.

The clamping device or pressure stop 15 comprises a rubber pad 15^a carried by the outer end of an arm 15^b which arm at its inner end is mounted upon the bearing carrying the spindle 18 in such a manner as to be friction tight so that it can be moved into any position desired. This spindle 18 serves to carry at its upper end the arm 16^a of the buckling device but in this case the arm 16^a is fixed to the spindle 18 so as to turn with it. At its outer end the arm 16^a carries a plunger fitted at its lower end with a pad or finger.

This plunger may be spring controlled as shown or arranged to fall by gravity. The lower end of the spindle 18 is provided with a crank arm 19 having a pin or the like 20 at its outer end which pin or the like is adapted to be engaged at intervals by means of a projection 21 carried by a bar 22. The bar 22 is carried by its ends in parallel slots 23 in a pair of side members 24 depending from and fixed to the underside of the frame 9 of the board 7.

The bar 22 is reciprocated within the slots 23 by means of crank pins 25 carried by toothed wheels 26 mounted upon each side of the frame of the press, the connection between said bar 22 and these crank pins being by way of a pair of connecting links 27.

The toothed wheels 26 are rotated by engagement with pinions 28 mounted upon the

outer extremities of one of the spindles 29 carrying a pair of the aforesaid sprocket wheels 4. The engagement between the pin 20 and the projection 21, in consequence of 5 the reciprocation of the bar 22, causes the spindle 18 to be rocked or partly rotated thus moving the buckling device 16 across the corner of the top sheet of paper the upper surface of which it frictionally engages through the medium of a rubber or other suitable pad 16^b coming in contact with the top sheet of paper by the action of the delivery board rising almost immediately after the rubber or pad has passed 15 over the extreme corner or edge of the paper.

This rocking or rotating movement of the buckling member takes place in predetermined relationship, in point of cycle, with 20 the movement of the board 7 to the raised position shown in Fig. 4. The normal tendency of the board 7 is to remain in the raised position under the action of the spring controlled roller 11, in which position the 25 clamping device or pressure stop 15 presses against the paper on the board and operates to provide an abutment to hold the paper at one position during the action of the buckling device.

30 The depression of the board and consequent release of the paper from the pressure of the clamping device or pressure stop 15 is effected by a paper retaining device 30 which is connected at its lower end to a 35 rod 31 carried at one end by a cam plate 32 whilst its upper extremity is bent over as at 33 for engagement with the edge of the stack of paper on the magazine or delivery board.

40 The cam plate 32 is attached as at 34 to an arm 35 which is pivoted at 36 to one of the side members 24. The front edge of the cam plate engages the periphery of a cam 37 mounted concentric with and movable with the toothed wheel 26.

45 This cam is provided with a segmental gap 38 into which the adjacent end of the cam plate drops, when the cam rotates, under the influence of a spring 39 as shown in Fig. 4. In this position of the cam plate 50 the paper retaining device 30 is in the raised position whilst as a consequence the delivery board is also raised and held by its spring with the paper pressed against the clamping device or pressure stop 15. The segmental gap 38 is of such a width as to maintain the 55 paper retaining device 30 in the raised position until the buckling device 16 has completed the removal of the engaged corner of the upper sheet of paper from under the bent over extremity of the retaining device 30.

60 When this removal of the paper has been completed the cam operates to depress both the cam plate and the paper retaining device 65 which latter device in consequence engages

the edge of the stack of paper on the magazine or delivery board except the top sheet and depresses the board against its spring thus relieving the pressure on the clamping device or pressure stop 15. The continued 70 movement of the toothed wheel 26 removes the projection 21 out of engagement with the pin 20 thus allowing the buckling device to swing under the influence of gravity 75 back to its normal position clear of the upper surface of the top sheet of paper.

Immediately the board begins to drop and engagement between the buckling device and the surface of the top sheet of paper ceases 80 the corner previously buckled returns to its normal flat position but above the head of the retaining device 30 over which the sheet passes when being transferred to the press.

The means for ensuring the transfer of the sheet to the press consists of a rubber 85 or other feeding finger 17 which is fixed to an arm 41, so as to project at right angles from it, this arm 41 extending transversely across the paper from one side of the delivery board 7 and the feeding finger 17 90 normally rests at an angle upon the surface of the paper on the board as shown most clearly in Fig. 1.

This feeding finger 17 is moved over the paper in consequence of the movement of 95 the bar 22 to which it is connected by means of a member 42.

When the feeding finger 17 approaches the end of its travel in the feeding direction it is raised clear of the finger by tripping 100 means. These means comprise a crank arm 43 on the end of the arm 41 and a slotted link 44 attached to said crank arm the slotted end of the link engaging a fixed pin or projection 45 on the frame of the delivery board which pin is so positioned as to engage the end of the slot in the link 44 just before the feeding finger reaches the limit of its travel in the feeding direction. Consequently the continued movement of the feeding 110 finger results in the backward movement of the crank arm 43 and the lifting of the feeding finger clear of the paper.

The paper as it is transferred from the delivery board by the feeding device is received by a clip 46 the two jaws of which are held normally open by the spring 47, closure of the clip being effected automatically by the impression roller 3 which also operates to lay each sheet flat upon the 120 chase or form.

It will of course be understood that a feeding device according to this invention can be used to feed sheets of flexible material other than paper, and into other printing presses than that referred to herein.

What I claim and desire to secure by Letters Patent is:

1. A feeding device for printing machines, comprising a magazine whereon the 130

paper to be fed is supported, a supporting clip adapted to engage the bottom edge of the stack of sheets of paper, means for releasing automatically the supporting clip when about to feed the top sheet, means for holding the sheets firmly at a point adjacent one of the lower corners of the upper sheet, means adapted to be periodically moved across and in contact with such lower corners of the top sheet whereby the sheet is buckled between such corner and the point where it is held and removed from beneath the supporting clip which is again returned to a position in engagement with the sheets and means for feeding the upper sheet forward into the machine when such sheet has been released from the buckling and holding means.

2. A feeding device for printing machines, comprising a magazine whereon the paper to be fed is supported, a supporting clip reciprocable in a direction normal to the plane of the sheets of paper, means for alternatively raising and lowering said clip out of and into engagement with the lower edge of the stack of sheets so as to alternatively release and secure the upper sheet of the stack of sheets, a plunger serving normally to press upon the upper sheet of paper at a point adjacent the corner which is held by the supporting clip, means for effecting periodically disengagement between said plunger and said upper sheet of paper, a swinging member, means for moving said member across and in engagement with the upper sheet of paper when the supporting clip is out of engagement with said sheet so as to buckle the corner of said sheet and move the same clear of the supporting clip and to hold such corner in this position until the supporting clip is returned to its normal position in engagement with the other sheets of paper on the magazine, said swinging member being adapted to be returned to its normal position out of engagement with the upper sheet of paper so as to permit the buckled corner of the upper sheet to return to a position above the supporting clip and means for engaging the upper sheet and feeding the same off the magazine over the remaining sheets of the stack.

3. A feeding device for printing machines comprising a magazine whereon the paper to be fed is supported, a supporting clip reciprocable in a direction normal to the plane of the sheets of paper, means for alternatively raising and lowering said clip out of and into engagement with the lower edge of the stack of sheets so as to alternatively release and secure the upper sheet of the stack of sheets, a plunger serving normally to press upon the upper sheet of paper at a point adjacent the corner which is held by the supporting clip, means for effecting

periodically disengagement between said plunger and said upper sheet of paper, a swinging member adapted to be oscillated across and in frictional engagement with the surface of the upper sheet of paper when the supporting clip is out of engagement with said sheet so as to buckle the corner of said sheet and move the same clear of the supporting clip and to hold such corner in this position until the supporting clip is returned to its normal position in engagement with the other sheets of paper on the magazine, said swinging member being adapted to be returned to its normal position out of engagement with the upper sheet of paper so as to permit the buckled corner of the upper sheet to return to a position above the supporting clip and means for engaging the upper sheet and feeding the same off the magazine over the remaining sheets of the stack.

4. A feeding device for printing machines comprising a magazine supported pivotally by its upper end and whereon the paper to be fed is supported, a pressure stop located above the paper adjacent one of the lower corners thereof, means for periodically raising and lowering the lower end of the magazine so as to force the paper towards and into contact with the upper sheet of paper and to move the same out of contact with said sheet of paper an arm adapted to be oscillated radially across and in frictional engagement with the surface of the upper sheet of paper when the lower end of the magazine is in the raised position whereby the sheet is buckled between the corner and the point where it is held by the pressure stop clamping means for normally holding the lower edge of the stack of sheets means for periodically releasing said clamping means to permit the corner of the upper sheet to be removed in consequence of the buckling operation and means for feeding the upper sheet, when released from the clamping means, over the clamping means and into the printing machine.

5. A feeding device for printing machines comprising a magazine supported pivotally by its upper end and whereon the paper to be fed is supported, a pressure stop located above the paper adjacent one of the lower corners thereof, means for periodically raising and lowering the lower end of the magazine so as to force the paper towards and into contact with the upper sheet of paper and to move the same out of contact with said sheet of paper, an arm adapted to be oscillated radially across and in frictional engagement with the surface of the upper sheet of paper when the lower end of the magazine is in the raised position whereby the sheet is buckled between

the corner and the point where it is held by the pressure stop clamping means for normally holding the lower edge of the stack of sheets, means for periodically releasing said clamping means to permit the corner of the upper sheet to be removed in consequence of the buckling operation, a pivoted

finger carried by a sliding carriage adapted to frictionally engage the surface of the upper sheet and feed the same forward over 10 the clamping means and into the printing machine.

In witness whereof I affix my signature.

CHARLES ASHTON HENRY BULLOCK.
